UNITED STATES PATENT OFFICE.

CHARLES LA DOW, OF ALBANY, NEW YORK.

DESIGN FOR A HARROW.

SPECIFICATION forming part of Design No. 19,820, dated September 24, 1889.

Application filed August 13, 1889. Serial No. 320,658. Term of patent 14 years.

To all whom it may concern:

Be it known that I, CHARLES LA Dow, of Albany, county of Albany, State of New York, have invented and produced a new and original Design for Harrows, of which the following is a specification.

The drawing is a plan view showing the design, which consists in a new shape for harrows. In this drawing the harrow-teeth are omitted from one-half of the frame.

The leading features of the design are:

First. The hexagonal openings A, of approximately diamond shape, flattened on opposite ends on lines transverse to the direction of travel of the machine. The lines bounding the openings have a transverse portion b, an oblique part c, a transverse part d, parallel with b, and an oblique part e, parallel with c, and so on for any desired number of openings, and the arrangement of openings is such that the flattened end of one opening

is at the middle angle of an adjoining opening.

Second. The configuration or shape of frame above described in connection with the curved figure presented by the harrow-teeth D, secured at the flattened ends of openings and projecting into them.

Third. In general outline the harrow is heart or V shaped, and between the two side groups of openings A are two approximately-rectangular openings F.

I claim—

The design for a harrow, substantially as herein described and shown.

In testimony whereof I have hereunto subscribed by name.

CHARLES LA DOW.

Witnesses:

EDWARD C. DAVIDSON,
M. J. KELLEY.
